UNITED STATES PATENT OFFICE

170,479

TEXTILE FABRIC OR SIMILAR ARTICLE

Ben Rose, Highland Park, Ill.

Application October 14, 1952, Serial No. 21,826

Term of patent 7 years

(Cl. D92—1)

To all whom it may concern:

Be it known that I, Ben Rose, a citizen of the United States, residing at 411 Pleasant Avenue, in the city of Highland Park, in the county of Lake and State of Illinois, have invented a new, original, and ornamental Design for a Textile Fabric or Similar Article, of which the following is a specification, reference being had to the accompanying drawing forming a part thereof.

The figure is a plan view of a textile fabric showing my new design. The dot and dash lines of the drawing outline a design unit, which unit is repeated in regular succession, as indicated by the extensions beyond the unit boundary.

I claim:

The ornamental design for a textile fabric or similar article, substantially as shown and described.

BEN ROSE.
